COILABLE, MOVABLE PARTITION

Kenneth J. Carlo, Dyersville, Iowa, assignor to New Castle Products, Inc., New Castle, Ind., a corporation of Indiana

Filed Dec. 19, 1966, Ser. No. 5,109

Term of patent 14 years

(Cl. D13—1)

FIG-1

FIG-5

FIG. 1 is a perspective view of a coiled, movable partition showing my new design;

FIG. 2 is a side elevation thereof;

FIG. 3 is a top plan view thereon on a slightly enlarged scale, and being partially broken away;

FIG. 4 is a bottom view thereof; and

FIG. 5 is an enlarged and partially broken away transverse section taken generally along the line 5-5 of FIG. 2. The broken lines are shown for illustrative purposes only.

I claim:

The ornamental design for a coiled, movable partition, substantially as shown and described.
